UNITED STATES PATENT OFFICE.

HUGH D. PEASLEE, OF FRESNO, CALIFORNIA.

CARBURETER.

1,107,103.

Specification of Letters Patent. Patented Aug. 11, 1914.

Application filed June 28, 1913. Serial No. 776,317.

To all whom it may concern:

Be it known that I, HUGH D. PEASLEE, a citizen of the United States, residing at Fresno, in the county of Fresno and State of California, have invented new and useful Improvements in Carbureters, of which the following is a specification.

This invention relates to force feed mechanical carbureters, the object of the invention being to provide a carbureter which is adaptable to a variety of fuels, enabling the fuel, in accordance with the nature thereof, to be measured automatically and supplied to the combustion chamber of the motor in the proper quantity and at the proper time.

While the invention will be hereinafter described as applied to a motor, embodying a single cylinder or combustion space, it is to be understood that the principle is applicable to motors having any number of cylinders and combustion spaces.

A further object of the invention is to provide a carbureter of the class referred to which is adapted to handle more than one kind of fuel at a time, as for example, a quick acting fuel such as gasolene of a high grade, and a low grade fuel, such as kerosene, which explodes comparatively slowly but contains great heat value. It will also handle an explosive gas, such as acetylene, and a low grade liquid or gas fuel.

With the above and other objects in view, the invention consists in the construction, combination and arrangement of parts, as will be hereinafter more fully described, illustrated in the accompanying drawings, and pointed out in the claims hereunto appended.

In the drawings: Figure 1 is a side elevation of a carbureter embodying the present invention. Fig. 2 is a vertical diametrical section through the same. Fig. 3 is a horizontal section taken in line with the slide which varies the capacity of the fuel pocket. Fig. 4 is a vertical diametrical section similar to Fig. 2, showing a plurality of pockets and slides.

The carbureter contemplated in this invention comprises the two main members 1 and 2, both of said members being cylindrical in shape and concentric, the outer member 1 being stationary and the inner member 2 being adapted to turn within the outer member either with an oscillatory or

complete rotary movement. Under the preferred embodiment of the invention, the inner member 2 is mounted on and carried by a rotary shaft 3 which, in a four-cycle engine, is driven at the same speed as the cam shaft, so that a charge of fuel will be supplied by the carbureter to the combustion chamber of the motor once in each two revolutions of the engine shaft or once in each complete revolution of the cam shaft, the fuel being supplied to the combustion chamber just before the time of ignition, and after the suction stroke of the piston has filled the combustion chamber with air.

The inner member 2 is provided with a fuel pocket 4 extending transversely and radially through the same with respect to the center of movement of said member, as illustrated in Fig. 3. This pocket, which may be of any size, is preferably rectangular in cross section, and within said pocket is mounted a slide 5, the outer end of which forms the inner wall of the fuel pocket, the slide 5 working with a snug sliding fit in said pocket.

The means for operating the slide 5, so as to vary the capacity and depth of the pocket 4 embodies a spindle 6 which forms an extension of the shaft 3, and turns therewith at the same speed. Mounted to slide lengthwise of the spindle 6 is a slide operating member or traveler 7. This traveler carries at one side of the spindle 6 a pin 8 which passes through an inclined or oblique slot 9 in the slide 5, so that as the member 7 moves lengthwise of the spindle 6, the slide 5 is moved inwardly or outwardly, according to the direction of movement of the member 7.

At one end the member 7 is provided with a collar 10, to which are pivotally connected one set of arms 11 of a speed governor, embodying a second series of arms 12 and weights or balls 13 which move outwardly by centrifugal action, in accordance with the speed of rotation of the spindle 6, the arms 12 of the governor being pivotally connected, at 14, to the spindle 6, so that the arms 11, when the balls 13 move outwardly and inwardly, transmit motion to the collar 10, and therefore to the member 7, causing the latter in turn, through the medium of the pin 8 and slot 9, to draw the slide 5 inwardly or move the same outwardly.

The mechanism just above described operates automatically to shift the member 7 for

correspondingly shifting the slide 5 and varying the capacity of the pocket.

In some cases, it is important to be able to manually control the size of the pocket, and I, therefore, show means for accomplishing this, the said means embodying a ring 15 extending around the spindle 6 at one side of the member 7, said ring being connected to an operating stem 16 which extends through a central longitudinal bore in the spindle 6, and is provided at its outer end with a grooved collar 17, to which a suitable hand-controlled lever is connected. By operating this lever, the member 7 may be shifted along the spindle 6, so as to correspondingly actuate the slide 5. A spring 18 bears against the collar 10 above referred to, said spring acting to move the member 7 in such direction as to actuate the slide 5 outwardly for reducing the size of the fuel pocket, when the speed of the spindle 6 is reduced.

The outer member 1 is provided with a fuel inlet or supply passage 19 in one side thereof, and adjacent thereto and in the same side thereof is a fuel overflow passage 20 which leads back to the fuel tank, from which fuel is fed to the supply passage 19, the said fuel supply tank and the necessary piping from the same to the member 1 not being shown. At the opposite side, the member 1 is provided with a pressure inlet passage 21, and a fuel outlet passage 22 arranged to be thrown into communication 35 with each other, when the pocket 4 registers therewith.

In Fig. 3, the passages 19 and 20 are shown as arranged substantially opposite the passages 21 and 22, so that in the rotation of the member 2, the pocket 4 will at one time register with the passages 19 and 20 and receive a certain charge of fuel, and subsequently register with the passages 21 and 22 so that the said charge of fuel may be expelled from the pocket and carried into the combustion space of the motor. A supply of air under pressure from a suitable storage tank or air compressor is admitted constantly to the passage 21, and, therefore, when the pocket 4 registers with the passages 21 and 22, the fuel is expelled from said pocket by air pressure, and thus carried positively in a predetermined quantity to the cylinder or combustion space of the motor. The fuel which is admitted to the pocket through the passage 19, after filling the pocket, overflows through the passage 20 back to the fuel tank. This insures filling the pocket with fuel and takes care of the surplus fuel, thereby insuring a complete filling of the pocket with fuel, irrespective of the position of the slide 5 which controls the size of the pocket.

It will, of course, be understood that while I have shown only one set of passages 19, 20,

21 and 22 adapted for use in connection with a single cylinder or combustion space, any number of sets of such passages may be provided, in accordance with the number of cylinders or combustion spaces, so that in each 70 complete revolution of the member 2, all of the cylinders will be supplied with charges of fuel, each combustion space getting its proper proportion of fuel. As the speed of the engine increases, when extra load or duty is imposed thereon, the size of the fuel pocket is automatically increased, thereby supplying the cylinders with a greater amount of fuel. This governor can be used 75 to prevent an increase of engine speed, for 80 stationary and truck work.

In some cases, it is desirable, for the sake of economy, to use more than one kind of fuel, and in Fig. 4, I have illustrated the device as comprising two fuel pockets 4' and 4'', using, in connection therewith, two slides 5' and 5''. It is thought unnecessary to go into a further description of the arrangement shown in Fig. 4, as it corresponds exactly with the showing made in Figs. 1, 2 90 and 3, except that the slides and pockets are duplicated, and it will also be understood that the number of passages to admit the fuel to the inner member and provide for expelling the fuel therefrom will be correspondingly duplicated.

The construction illustrated in Fig. 4 enables the motor to be fed with two kinds or grades of fuel such, for example, as kerosene, and acetylene or other gas.

The carbureter hereinabove described will enable higher compression to be obtained, without pre-ignition.

The construction is exceedingly simple and renders it possible to use only one valve 105 in the engine to perform the function of both the present inlet and exhaust valves. It also makes it possible to thoroughly mix different fuels and to use gas as well as liquid for fuel. A perfect control of the quantity of fuel is obtained, causing each cylinder to be supplied with exactly the same amount of fuel. Perfect combustion is obtainable, and the carbureter may be used without any danger of strangling or starving the engine at any speed, a common occurrence with the present type of float feed carbureter.

It is believed that the carbureter of this invention will also solve the back-firing and pre-ignition troubles now present in two-cycle engines, and will also increase the efficiency of revolving and other aeronautical motors. Furthermore, it will economize in the fuel consumption of all internal combustion engines, by reason of the fact that the fuel is practically measured for each and every cylinder. The carbureter *per se* has no springs or weights and does not depend upon suction. The operator may readily

control the amount of fuel and the liability of the carbureter being clogged is reduced to a minimum, by reason of the simple construction involved.

- 5 By using a separate carbureter for each cylinder, it will be possible to introduce the fuel into the cylinder, or combustion chamber without the aid of a compressed air tank. The inner member containing the fuel
- 10 pocket can be rotated in such manner that the pocket is exposed to the compressed gas in the cylinder, which will force the fuel out of the pocket or pockets. The result can also be obtained by oscillating the inner member and placing the outer member or casing therein in communication with the compression chamber of the engine cylinder so as to receive pressure therefrom to eject the liquid or other fuel.
- 15 20 What is claimed is:
1. In a carbureter, outer and inner concentric cylindrical members, the outer member being stationary and the inner member being mounted to turn within the outer member, the inner member being formed with a fuel pocket in its external face, and the outer member being formed with fuel supply and overflow passages with which said pocket is adapted to register and also formed with pressure inlet and fuel outlet
- 25 30

passages with which said pocket is adapted to register subsequently to the registration first mentioned, and governor mechanism contained within said inner member for automatically varying the fuel holding capacity of said pocket. 35

2. In a carbureter, outer and inner concentric cylindrical members, the outer member being stationary and the inner member being mounted to turn within the outer member, the inner member being formed with a fuel pocket in its external face, and the outer member being formed with fuel supply and overflow passages with which said pocket is adapted to register and also formed with pressure inlet and fuel outlet passages with which said pocket is adapted to register subsequently to the registration first mentioned, means for varying the fuel holding capacity of said fuel pocket, embodying a slide forming a wall of said pocket, and governor mechanism contained within said inner member and operatively connected with said slide for shifting the latter in said pocket. 40 45

In testimony whereof I affix my signature 50 55 in presence of two witnesses.

HUGH D. PEASLEE.
